(57) **CLAIM**

The ornamental design for a shaving aid strip for a razor cartridge, as shown and described.

DESCRIPTION

FIG. 1 is a perspective view of a shaving aid strip for a razor cartridge showing our new design;

FIG. 2 is a side elevation view thereof, the other side elevation view being a mirror image thereof;

FIG. 3 is a top plan view thereof;

FIG. 4 is a front elevation view thereof;

FIG. 5 is a rear elevation view thereof;

FIG. 6 is a side elevation view of a second embodiment of the shaving aid strip of FIG. 1, the other side elevation view being a mirror image thereof; and,

FIG. 7 is a top plan view of the shaving aid strip of FIG. 6. The broken line which defines the lower boundary of the claimed design forms no part thereof.

The broken lines showing the razor cartridge and parts underlying the broken line boundary are for illustrative purposes only and form no part of the claimed design. The stippling represents a color contrasting surface.
